Patented Aug. 14, 1917.

FIG. 1

INVENTOR.

H. N. FRIEND

BY *Milton S. Crandall,*
ATTORNEY.

UNITED STATES PATENT OFFICE.

RICHARD NASON FRIEND, OF SIOUX CITY, IOWA.

FLASH-LIGHT.

1,237,191.

Specification of Letters Patent. Patented Aug. 14, 1917.

Application filed December 9, 1916. Serial No. 135,937.

To all whom it may concern:

Be it known that I, RICHARD NASON FRIEND, a citizen of the United States, and a resident of Sioux City, in the county of 5 Woodbury and State of Iowa, have invented certain new and useful Improvements in Flash-Lights, of which the following is a specification.

The present invention relates to flash-lights and more particularly to means for the support thereof.

The invention has for its object the production of an improved support for cylindrical flash lights embodying certain novel 15 features whereby the flash-light may be supported at any angle desired.

Another object of the invention is the production of a flash-light support, inexpensive in manufacture and thoroughly dependable 20 in use, adapted to be instantly adjusted to and from its operative position and adapted, when not in use, to be unobtrusive.

With these and other objects in view, the invention will be fully understood from the 25 following description, reference being had to the accompanying drawings which form a part of this application and in which like characters of reference indicate corresponding parts throughout the several views, of 30 which,

Figure 1 is a plan of a flash-light equipped with the embodiment of my invention, the supporting member being in position as when not in use; Fig. 2 is a side elevation 35 of the same, the support being in operative position; and Fig. 3 is an isometric view of the support.

Referring now to the illustrations, the flash-light shown is of the familiar cylindrical type having a barrel, 4, a lens, 5, at 40 its forward end and a rear end cap, 6.

These lights are commonly used for illuminating mechanism or material of other sort, for locating faults, making repairs, and so 45 forth. Their use, however, has been most inconvenient for when it becomes necessary for the operator to apply both hands to the work the flash light can only be supported by laying it down, making it impossible to 50 direct the rays of light advantageously. I obviate this defect by providing a support preferably comprising a base ring, 7, of sub-

stantially the same diameter as the end of the barrel of the flash-light case.

Formed integrally with the diametrical 55 side of the ring are parallel uprights, 8, the ends of which are riveted as at 9, or otherwise pivotally-secured to opposite sides of the barrel at the center of gravity of the flashlight, whereby the light is balanced. 60 The pivots, 9, are sufficiently tight to retain the flash-light in any position in which it is placed with respect to the uprights and still permit the light to be tilted at any desired angle as clearly shown by dotted lines in 65 Fig. 2. The uprights are sufficient in length to permit the support to be swung rearwardly in parallelism with the barrel when not in use. In the present embodiment the rear end of the barrel or cap is convex as 70 at 10, and so related to the ring that when the support is swung rearwardly the base ring, 7, will be sprung over and engaged by the end of the barrel, which normally prevents displacement of the ring from the said 75 end. The uprights may be provided with off-sets as at 11, to accommodate the enlarged portion of the barrel and still permit the uprights to lie close against the side of the barrel as shown in Fig. 1. 80

Having thus described my invention what I claim as new and desire to secure by Letters Patent of the United States, is,—

1. A support for a flashlight having an elongated case, comprising a base and uprights thereon adapted to be pivoted to opposite sides of the case at substantially the center of gravity of the flashlight, the support being adapted to be turned on its pivots to place the uprights longitudinally of the 85 case and the base at the end thereof.

2. A support for a flashlight having a cylindrical case, comprising a circular base and uprights thereon adapted to be pivoted to opposite sides of the case at substantially 90 the center of gravity of the flashlight, the support being adapted to be turned on its pivots and place the base coaxially with the case. 95

3. A support for a flashlight having an elongated case, comprising a base plate and uprights thereon adapted to be pivoted to opposite sides of the case at substantially the center of gravity of the flashlight, the sup- 100

port being adapted to be turned on its pivots and spring the base over the end of the case.

4. The combination with a flash-light including a cylindrical case having a convex end, of a support consisting of a base ring, and uprights formed integrally with diametrically opposite sides thereof and pivoted at their upper ends to opposite sides of the

case at substantially the center of gravity of the flashlight, the support being adapted to 10 be turned on its pivots and spring the ring over the convex end.

In testimony whereof, I have hereunto set my hand this 6th day of December, 1916.

RICHARD NASON FRIEND.
